UNITED STATES PATENT OFFICE.

MAURICE BLUMENTHAL, OF BROOKLYN, NEW YORK.

ROOFING PAPER.

Application filed March 29, 1919. Serial No. 286,127.

To all whom it may concern:

Be it known that I, MAURICE BLUMENTHAL, a citizen of the United States, and resident of Brooklyn, in the county of Kings and State of New York, have invented certain new and useful Improvements in Roofing Paper, of which the following is a specification.

This invention relates to roofing papers such as are employed for surfacing roofs or for analogous purposes. While my invention has special relation and adaptability to surfacings for roofs, it will be understood that the paper or composite body sheet as produced by my improvements may be employed in any other conditions or uses for which a product of this type is adapted.

Roofing papers of the type to which my invention relates have usually heretofore been formed of a felt-paper body which is impregnated or saturated with a compound formed of tar or asphaltum or other water-proof elements and has affixed over its top surface a fine gravel or pulverized pebbles. In this construction, the gravel or pebbles are liable to penetrate or puncture the paper body under pressure, and they produce a very uneven and irregular tread surface and also limit the pliability or flexibility of the composite body. Furthermore, roofing papers of this common type are deficient in fireproof character and are liable to damage by tearing in handling or in other conditions of laying or use.

The object of my invention is to overcome the above-noted objections and disadvantages, and to provide an improved roofing paper or surfacing sheet of the character set forth, which can be more economically and effectively manufactured, which will be pliable and flexible under all conditions, which will be effectively fire-resisting, and which will furthermore possess advantages in point of strength, durability, convenience, inexpensiveness, effectiveness, and general efficiency.

In the drawings—

Figure 1 is a plan view of a portion of a length of the improved roofing paper or surfacing sheet, partly broken away to show the underlying construction.

Fig. 2 is a detail cross-section on an enlarged scale, taken on the line 2—2, Fig. 1.

Fig. 3 is a plan view, corresponding to Fig. 1, illustrating a modified condition of construction.

Corresponding parts in all the figures are denoted by the same reference characters.

My improved roofing paper or surfacing sheet is constituted by a composite body which comprises two body sheets, 1—1, respectively forming top and bottom members. Said body sheets are formed of a suitable pliable or flexible material, preferably felt paper, though they may be constituted by a textile or fibrous or other absorbent or adapted material. The body sheets 1—1 are superposed and united and adhesively secured together over the area of their opposed surfaces by a suitable adhesive compound, 2, to produce a composite body sheet, which compound is also taken up or absorbed by the superposed sheets so that the latter are impregnated or saturated therewith. The uniting and saturating compound has a water-proof character, and may be a tar or asphaltum composition, but I prefer to employ a compound which will impart to the composite body sheet a water, acid and fume proof character, and for this purpose the compound may consist of animal or vegetable fats or oils combined with mineral waxes, such as ozocerite, mineral caoutchouc, gilsonite, or retinite, which compound will have a melting point approximately 375° F. and a permanently adhesive or "tacky" and impervious quality.

Over the surface of the impregnated top sheet 1 is laid an outer surfacing of mica scales, as at 3, which adhere to the sheet and maintain a permanent status with relation thereto. The mica surfacing is applied to the sheet by pressure, preferably under a high degree of hydraulic pressure, and the mica scales are affixed in scattered position so that they cover the full outer surface of the sheet and form the tread surface of the roofing paper. There is thus produced a substantially smooth tread surface which will not puncture or penetrate the underlying sheet, which is very tough and durable and which will resist a high degree of heat and is itself water, acid and fume proof. The mica scales are scattered in their positional lay over the sheet 1 so that they overlap, as indicated at 4, thus ensuring a complete surface covering affording a pliable laminæ which will not detract from the flexibility or pliability of the composite sheet but will operate as a reinforce therefor and as a resistance against tearing of or damage to sheet. I

prefer to first grind mica to produce the small and thin scales which are employed for the tread surfacing as above described and which constitute a very inexpensive 5 and easily applied element in the manufacture of the improved product constituting my invention.

In the preferred construction, there is also placed intermediately of the superposed 10 body sheets 1-1, and in association with the uniting and impregnating compound 2, a fibrous filler, 5, which is spread and sandwiched between the body sheets over the general area of the opposed surfaces 15 thereof and forms an effective supplementary reinforce against strain or tearing in any and all directions. Said fibrous filler preferably consists of asbestos suitably ground into strings or fibers, which 20 filler will also enhance the fire-resisting quality and the strength and durability of the composite sheet as produced according to my invention, but the filler under some circumstances of use may consist of cotton 25 waste or cotton sweepings or other suitable or desired fibrous material.

I have illustrated in Fig. 3 a modified construction in which, as a further resistance to tearing or damage of the composite 30 sheets in handling or in use, and to enhance the strength and durability of the product, longitudinal strips, as at 6-6, are located 35 respectively at the side edges of the composite sheet intermediate of the body sheets 1-1 and in association with the uniting adhesive and impregnating compound 2. These strips are of suitable width, so that 40 they reinforce the area of the edge portions of the composite sheet at all points extending from the actual plane of the 45 edge, and they are formed of a suitable pliable material, preferably a textile or mesh fabric, or a paper or fibrous material having sufficient strength as a reinforcement and as a preventive against tearing 50 of the edges of the composite sheet under any conditions of handling or in application or use. The strips or tapes may under 55 some conditions of use consist of an asbestos fabric. Corresponding longitudinal strips or tapes, as at 7, preferably wider than 60 said edge strips, are in the preferred construction of my improved composite sheet, according to the modification shown 65 in Fig. 3, located intermediately of the edge strips and at the central portion of the composite sheet, or they may be located at 70 intervals between the edge portions, said intermediate strips being in parallel relationship to the edge strips and likewise in 75 association with the uniting adhesive and impregnating compound between the body sheets 1-1.

Under some conditions of construction 80 according to my invention, the under body

sheet 1 may be dispensed with, so that the composite sheet consists of the top sheet 1 having the outer tread surfacing 3 of scales of mica or other analogous mineral substance and the impregnating and adhesive 70 compound 2, with or without the fibrous filler 5 at the under side of said top sheet.

In the practical and economical manufacture of the improved composite sheet, the pliable body sheets 1-1 are passed through 75 pressure rolls, in association with the uniting and impregnating adhesive compound, under the action of suitable mechanism for feeding and placing the surfacing scales 3 and the intermediate fibrous filler 5 and also 80 the reinforcing strips or tapes 6 and 7 if the latter are employed, and pressure action is exerted to press together in securely associated position the several elements or members of the composite sheet.

85 The advantages of my improvements will be readily understood. The invention produces an improved composite sheet adapted for roofing or other analogous surfacing uses, which in its general characteristics is fire-resisting, waterproof, and flexible or pliable under all climatic conditions or circumstances of handling which affords a tread of outer surface which is substantially 90 smooth and is itself fire, water, acid and 95 fume proof, and which is furthermore extremely strong and durable and can be economically and effectively manufactured.

I do not desire to be understood as limiting myself to the detail features of construction as herein shown and described, as it is manifest that variations and modifications therein may be resorted to, in the adaptation of my invention to varying conditions of use, without departing from the spirit and scope of my invention and improvements. I therefore reserve the right to all such variations and modifications as properly fall within the scope of my invention and the terms of the following claims.

100 Having thus described my invention, I claim and desire to secure by Letters Patent:

1. An improved composite sheet of the class described, comprising superposed pliable body sheets united and adhesively secured together at their opposed surfaces by an adhesive compound and impregnated therewith, longitudinal reinforcing strips or tapes extending intermediately of said body sheets, and an outer surfacing consisting of scales of mica covering the surface of the top body sheet.

115 2. An improved composite sheet of the class described, comprising superposed pliable body sheets united and adhesively secured together at their opposed surfaces by an adhesive compound and impregnated therewith, a fibrous filler located in association with the uniting adhesive compound 120 intermediately of said body sheets and ex-

- tending over the general area of the opposed surfaces thereof, longitudinal reinforcing strips or tapes extending intermediately of said body sheets, and an outer surfacing 5 consisting of scales of mica covering the surface of the top body sheet.
3. As an improved article of manufacture, a composite sheet comprising superposed pliable body sheets united and adhesively 10 cured together at their opposed surfaces by an adhesive compound and having longitudinal flat reinforcing tape strips extending intermediately of said body sheets and in association with said uniting adhesive compound, said reinforcing strips having a 15 width corresponding to the area of the edge portions of the composite sheet and extending from the actual plane of the edge at all points thereon inwardly over the area of 20 the edge portions of the body sheets.
4. As an improved article of manufacture,

a composite sheet comprising superposed pliable body sheets united and adhesively secured together at their opposed surfaces by an adhesive compound and having longitudinal flat reinforcing tape strips extending intermediately of said body sheets and in association with said uniting adhesive compound, said reinforcing strips comprising edge strips having a width corresponding to 25 the area of the edge portions of the composite sheet and extending from the actual plane of the edge at all points thereon inwardly over the area of the edge portions of the body sheets and supplementary body 30 strips positioned intermediately of said edge strips and having a width area greater than that of said edge strips.

In testimony whereof I have signed the foregoing specification.

MAURICE BLUMENTHAL.
